3,270,600 FILM CUTTER

Kenneth H. Love, Urbana, Ill., assignor to The Magnavox Company, Fort Wayne, Ind., a corporation of Delaware

Filed Sept. 27, 1963, Ser. No. 312,199
24 Claims. (Cl. 83—94)

The present invention relates to means for cutting a continuous film into a plurality of substantially identical film cards which may be employed as a storage medium for use in data processing mechanism. More particularly, the invention relates to means for accumulating the film cards as they are being cut and storing the cards in a stacked relationship.

One method of filing documentary information involves the use of photography to record graphic and printed information in greatly reduced form on tiny pieces of film or film cards. In addition to containing the documentary information each card 16 is marked with machine readable coding. This will facilitate the mechanical processing of the cards in order to retrieve and/or use the documentary information contained upon the card. In order to produce the cards a continuous strip of unexposed film may be placed in a camera which is focused on a suitable target area. The various documents to be recorded and codings relating thereto may be serially disposed on the target area in sequence and the successive frames of the film exposed. When the whole film has been exposed it may be developed and the various frames cut therefrom to form the film cards. One means of accomplishing this cutting operation is to employ a film cutter such as that described and claimed in copending application, Serial Number 141,875, now abandoned, filed September 29, 1961 in the name of Leroy C. Kleist and assigned of record to The Magnavox Company. Such a machine is effective to intermittently advance the film one frame at a time through a cutting mechanism and to cut the frames from the film to provide the film cards. As the cards are cut from the film it is necessary to accumulate the cards so that they will be stored in a stacked relationship suitable for subsequent handling by a data processing machine.

Although the above mentioned film cutter employed means capable of accumulating the cards as they were being cut, it is now proposed to provide an improved means for receiving the cards and retaining them in a stacked relationship suitable for subsequent processing by data processing machine. More particularly it is proposed to provide card-receiving means which are not only simple and inexpensive to manufacture and use but are also trouble-free in operation. It is further proposed to provide receiving means that are not only easily handled but are also effective to receive the cards in a stack relation and retain them in such an accumulated relationship for storing and further machine processing without any manual handling of the individual film cards after they have been cut.

These and other features and advantages of the present invention will become readily apparent from the following detailed description of one embodiment therein, particularly when taken in connection with the accompanying drawings wherein like reference numbers refer to like parts, and wherein,

FIGURE 1 is a front elevational view of a machine embodying the present invention,

FIGURE 2 is a view of a developed film strip to be fed through the machine of FIGURE 1 and a film card that is cut from the film strip,

FIGURE 3 is a side view of a magazine with a storage capsule mounted therein for use on the machine of FIGURE 1,

FIGURE 4 is an end view of the magazine,

FIGURE 5 is a fragmentary cross-sectional view taken substantially along the plane of line 5—5 in FIGURE 3,

FIGURE 6 is a fragmentary cross-sectional view taken substantially along the plane of line 6—6 in FIGURE 3,

FIGURE 7 is a side view of the storage capsule mounted on the magazine in FIGURE 3,

FIGURE 8 is a transverse cross-sectional view of the capsule taken subsequently along the plane of line 8—8 in FIGURE 7,

FIGURE 9 is a bottom view of the storage capsule,

FIGURE 10 is a fragmentary perspective view of a portion of the storage compartment.

Referring to the drawings in more detail the present invention is particularly adapted to being embodied in a machine 10 for receiving a reel 12 containing a strip of film 14 and cutting the film into a series of cards 16 of substantially the same size and shape.

Although this film may be of any desired variety and may contain any desired type of information, in the present instance the film strip 14 includes a series of frames 18 which are all of substantially the same size and shape. The frames 18 are separated from each other by a plurality of apertures or openings 20 that are relatively long in relation and extend transversely across the film strip 14.

Each of the frames of film 18 includes a document section 22 and a data processing section 24. The document section 22 is adapted to have one or more photographic images of documents, letters, drawings, etc., contained thereon. The data processing section 24 may include a plurality of photographic images that are machine readable and relate to the documentary material contained in the juxtaposed document section 22. This area will be effective to permit a machine to conduct a search through a number of the cards 16 to retrieve the documentary material contained in the document section 22 of a particular card.

In order to expose the frames 18 of film strip 14 a camera may be provided that employs a long strip of unexposed film. The camera is focused on a target area where the various documents and data processing information are placed. The various frames 18 of the film strip 14 are successively exposed. After the entire film strip 14 has been exposed, then the negative may be removed from the camera and developed to bring out the latent images present on the frame 18. The resultant strip 14 of the film may then be wound on reel 12.

In order to use the developed film it is desirable that it be cut into a plurality of chips or film cards 16 with each card 16 containing a single frame 18. In order to accomplish this the continuous strip 14 of film may be fed from the reel 12 and through the machine 10. The machine 10 will be effective to simultaneously cut the film strip 14 into a plurality of substantially identical cards 16 and stack the cards 16 into stacks of substantially uniform size.

The present machine or film cutter 10 includes a front panel 28 which may be substantially vertical and exposed so as to be readily accessible to an operator. A shaft 30 is provided that projects outwardly from the panel 28 for receiving the reel 12 of exposed and developed film. This shaft 30 is not driven but is effective to allow the reel 12 to rotate about its axis while the film 14 is being unwound therefrom. In addition, the panel 28 has on its front side a film transport mechanism 32, a cutter mechanism 36, a section 38 having the controls for controlling the operation of the film transport mechanism 32 and cutter mechanism 36 and means 40 for receiving the film cards 16 as they are cut from the film strip.

The film transport mechanism 32 includes a wheel or sprocket 42 that has a plurality of teeth or spokes 44

thereon. The spokes 44 are circumferentially spaced at intervals that are substantially equal to the space between the openings 20. The ends of the spokes 44 will thus extend through the openings 20 and provide a positive drive for the film 14. A film guide 46 is disposed adjacent the sprocket 42 so that the film strip 14 passing over the wheel 42 may slide therethrough and emerge from the end 48.

The cutter mechanism 36 is disposed adjacent the guide 46 and includes a cutting head 50 for travelling up and down and moving toward and away from the film strip as it emerges from the guide 46. The cutting head 50 includes a cutting edge 52 on one end that is in substantial alignment with the end 48. The end 48 and the blade 52 will be effective to act as a shears when the head 50 descends so as to cut the terminal frame 18 from the film 14 to form a film card 16. The cutting head 50 may also include a projection or foot 54 that is adapted to engage the card 16 as it is being cut and to force it into the means for receiving the cards 16.

The section 38 includes one or more switches 56, 58 and 60 that are effective to control the operation of the film transport mechanism 32 and the cutter mechanism 36. The switches 56, 58 and 60 are interconnected with drive means (not shown) that supply the power for running the mechanisms 32 and 36.

Although any suitable drive mechanism may be employed, in the present instance the drive mechanism is substantially identical to that disclosed and claimed in copending application "Film Cutter," Serial No. 144,875, filed by Leroy C. Kleist and assigned of record to The Magnavox Company. In such a film cutter, a drive motor is provided, which is operatively interconnected with the sprocket 42 and with the cutter head 50 for operating them. When the mode selector switch 56 is placed in a MANUAL position, the feed switch 58 may be energized to cause the sprocket 42 to rotate continuously and feed the film strip 14 through the cutter mechanism 36 without film being cut. Alternatively the single cut switch 60 may be closed so as to cause the cutter mechanism 36 to cut a single film card 16. If the mode selector 56 is placed in the AUTOMATIC position the drive motor will be effective to intermittently step the drive sprocket 42 through an arc substantially equal to the angle between the spokes 44 on the sprocket 42. This will in turn intermittently advance or step the film through the guide 46 by increments that are substantially equal to the length of one frame 18. Following each advance, the sprocket 42 will momentarily stop to position the terminal frame of the film strip 14 adjacent the end of the guide 46 and in substantial alignment with the cutter. Preferably the frame 18 will be positioned so that one edge of the aperture 20 will be aligned with the end 48 of the guide 46 and the blade 52. While so positioned, the cutter will descend so that the cutting edge 52 thereon will cut the film along one edge of the opening or aperture 20 and provide a film card 16. This card 16 will contain the terminal frame and will have a substantially straight edge 62 on one end and a matching edge 64 on the other end.

Each time a card is cut, the foot on the cutter head 50 will engage the card 16 and transfer it onto a stack of cards in the receiving means 40. Although this means may be of any suitable variety, in the present instance it includes a magazine 66 which has a handle 68 on one side that is of sufficient size to permit a person to easily carry and utilize the magazine 66. As best seen in FIGURE 3, the magazine 66, in addition to having a handle 68, has a bottom portion 70 and a pair of parallel arms 72 and 74. The bottom portion 70 includes a guide such as a groove 76 along one side which is adapted to fit into and ride along a track 78 mounted on the front panel 28. A detent such as a spring biased pin 80 may be provided on the track 78 or the bottom portion 70 of the magazine. This will be effective to releasably re-

tain the magazine positioned immediately under the cutter mechanism 36.

The two arms 72 and 74 are disposed substantially parallel to each other to provide an upwardly directed opening. When the magazine 66 is locked in position on the track 78, the opening will be disposed in substantial alignment with the foot 54 on the cutter head 50. A bracket or member 82 may be disposed between the two arms 72 and 74 at a point about half way between the top and bottom of the arms.

In addition, one or more capsules 84 may be provided which are adapted to be mounted on the magazine 66 in the space between the two arms 72 and 74. Each of the capsules 84 is effective to receive the cards 16 as they are cut and accumulate a stack of the cut cards. Also, the capsule 84 may be employed for storing the stacks of cards 16 so that they will be available for future use in suitable data processing means. Although the capsules 84 may be fabricated in any suitable manner, in the present instance the capsule 84 is fabricated out of a single piece of sheet metal. More particularly, a pair of elongations on the opposite ends of a base 86 may be bent into a U shape and then bent at right angles to the base 86. These will thus form a pair of end walls 88 that include a pair of flanges 90 that extend part way along the sides of the capsule 84.

Another pair of elongations may be provided on the opposite sides of the base 86 and bent upwardly to form a pair of side walls 92 and 94 that fit between the flanges 90 carried by the end walls 88. These side walls 92 are free standing from their lower ends and function as cantilever springs. The free ends of the side walls may thus be resiliently deflected toward and away from each other. The walls 88, 92 and 94 are arranged to form a rectangular compartment which has a cross sectional shape substantially identical to the size and shape of the cards 16. It will thus be seen that a plurality of cards 16 may be arranged in a stack 96 that will just fit into the compartment and between the walls.

The upper ends of the walls 88, 90 and 92 are normally positioned so that they will provide an opening 98 into the compartment to permit the cards 16 to pass therethrough and into and out of the compartment. Each of the ends may include a pair of flanges or lips 100 which project inwardly toward each other. These lips 100 extend inwardly a sufficient distance to bear upon the end card in the stack 96. These lips 100 are preferably of sufficient size to effectively prevent the film cards from being removed from the capsule. Although it is desirable to be able to easily remove the cards and insert them into the compartment, the lips are preferably of sufficient size to extend a substantial distance over the cards to prevent accidental removal of the cards as a result of dropping the capsule 84.

A plunger 102 may be reciprocably disposed inside of the compartment to engage the inner end of the stack 96. A spring 104 is provided that acts against this plunger 102. This will in turn bias all of the cards in the stack 96 upwardly and maintain the end card tightly compressed against the lips 100. Thus, all of the cards 16 will be neatly compressed toward the end of the capsule 84.

The space between the exterior of end walls 88 may be substantially equal to the inside distance between the arms 72 and 74 of the magazine 66, while the width of the end walls 88 is equal to the thickness of the arms. As a consequence, the capsule 84 is adapted to just fit between these arms and be retained in position thereon. The top of the member 82 is positioned so that the base 86 of the capsule 84 will rest thereon and the top of the capsule 84 will be positioned adjacent the ends of the arms 72 and 74.

It has been found desirable to provide a plunger 106 and spring means 108 below this member 82. An elongated stem 110 may be provided on the top of the plunger 106 to project upwardly through the member 82 and an

opening 112 on the bottom 86 of the capsule 84 and engage the card stack 96. The stem 110 will provide an additional force for biasing the film cards toward the top of the capsule 84.

It has also been found desirable to provide a lock means to retain the capsule 84 in position between the arms. In the present instance this means includes a lever 116 that is pivotably secured on top of the magazine 66. On one end of the lever 116 is secured to the top of the arm 74 by means of a hinge pin 118. This will permit the lever 116 to swing between a raised position and a lowered position. The lever 116 includes a pair of parallel arms 120 that are separated from each other. When the lever 116 is swung into the raised position, the opening between the two arms 72 and 74 will be clear. As a consequence, a capsule 84 may be easily inserted in position between the arms 72 and 74 or may be removed therefrom.

When the lever 116 is swung in to the lowered position the arm 120 thereon will bear against the top of any capsule 84 present in the magazine 66. In order to retain the lever 116 in this lowered position and thereby lock the capsule 84 in position, a suitable detent mechanism 122 may be provided.

In the present instance, as may be seen in FIGURE 5, this detent means includes a spring biased pin 124 which is carried by the magazine 66 so as to extend from one side thereof and fit into an opening 126 on the side of the lever 116. A plunger 128 may be disposed in this opening 126 and have an enlarged head 130 on one end thereof. The head 130 may be disposed adjacent the handle 68 so as to be convenient to operate. Thus, an operator holding the magazine 66 by the handle 68 in one hand may depress this head 130 with a finger on that hand. When depressed, the pin 124 will be driven out of the opening 126 and the lever 116 will be free to swing out of position.

Each of the arms 120 on the lever 116 may also include a pair of downwardly projected flanges 132 which are positioned to engage and separate the side walls 92 and 94 from each other. More particularly, each of the side walls 92 and 94 may have an outwardly bent tab 134 disposed between the lips 100. When the lever 116 is in the lowered position, flanges 132 engage the two tabs 134 on the side walls 92 and 94 as seen in FIGURES 8 and 10. This will cause the side walls to be resiliently deflected outwardly about the bottom edges to the dotted positions 136. This, in turn, will cause the lips 100 to be separated a sufficient distance to permit the cards 16 to pass therethrough. To prevent the loss of the cards 16 from the capsule 84 the lever 116 may have a plurality of lips 138 provided along the edges of the arms 120. These lips 138 are just sufficiently large to retain the cards 16 in the capsule 84 against the force of the springs 104 and 108. However, the lips 138 are sufficiently far apart to permit the cutting mechanism to easily drive a card 16 therethrough as it is being cut from the film strip.

It will thus be seen that an inexpensive and simple means has been provided which is effective to receive the film cards as they are being cut and retaining them in a stacked relationship convenient for future use in data processing equipment. More particularly, to employ the present apparatus, the reel 12 containing the strip of uncut film 14 may be mounted on the spindle 30. The film is then laid across the sprocket 42 and fed into the guide 46.

The lever 116 on the magazine 66 may then be raised and a capsule 84 positioned between the two arms 72 and 74. The lever 116 is then swung into the lowered position until the pin 124 snaps into the opening 126 and locks the lever 116 in a lowered position. The capsule 84 will then be securely locked into position on the magazine 66. By grasping the handle 68 the operator can conveniently handle the magazine 66 and the capsule 84 therein. The bottom portion of the magazine 66 may 70

then be positioned on the track 78 and slid thereacross until it is locked in position by means of the detent 80. At this point the capsule 84 will be positioned immediately below the cutter head 50 with the opening in its top in substantial alignment with the foot 54.

The mode selector switch 56 may be then moved to the MANUAL position and switch 58 closed. The film or its leader will then be fed through the cutter to the point where it is desired to start cutting cards. The leader may then be cut off by closing switch 60 and the switch 56 moved to the AUTOMATIC position. This will cause the sprocket 42 to intermittently advance the film a frame at a time through the film guide 46.

At the same time each time the film stops the cutter head 50 will be stroked up and down whereby the edge 52 will cut the terminal frame from the film strip 14. The projection on the foot 54 will simultaneously engage the resultant card and force it downwardly. The card will then be forced through the opening 140, defined by the inner edges of the arms 120. The card will pass between the lips 138 and onto the stack of cards contained within the capsule 84. Since the flanges 132 will be retained in intimate engagement with the tabs 134, the side walls 92 and 94 will be deflected outwardly toward the dashed position 136 (FIGURE 8). As a consequence, the lips 100 will be separated a sufficient distance to permit the cards to freely pass therethrough.

As the cards are cut, the length of the stack 96 will grow and the plungers 102 and 106 will gradually descend. When the desired number of cards have been cut or the capsule 84 contains a complete stack of cards, the mode selector switch 56 may be moved to the MANUAL or "ON" position. This will stop the sprocket 42 and cutting head 50 from cutting any further cards.

In order to prevent overloading of the capsule it has been found desirable to provide a switch 142 which is mounted adjacent the track 78 so that an arm 144 thereon will project into the side of the magazine 66. When the capsule 84 contains a full stack of cards, the plunger 106 will have descended to a point where an arm 146 on the side thereof will engage the arm 144. Further filling of the capsule 84 will result in depressing the arm 144 and opening the switch 142. This in turn will stop the operation of the entire machine and prevent any further cutting of the cards 16.

When the capsule 84 has been loaded with the desired number of cards 16 and the machine 10 has stopped, the operator may grasp the handle 68 and pull the magazine 66 from the machine 10. The button, or head 130 may then be manually depressed to release the lever 117. As the lever 116 swings upwardly the flanges 132 will disengage the tabs 134 and allow the lips 100 to move inwardly and retain the cards locked in position.

It should be noted that normally the lips 138 are disposed above the lips 100 and as a consequence some cards may be disposed outside of the lips 100.

To prevent the loss of these cards it has been found desirable to manually push the stack of cards 96 into the capsule 84 as the lever 116 is being raised.

After the loaded capsule is removed from the magazine 66, an appropriate label may be provided on the flange 148 to indicate the type of cards that are contained within the capsule 84. The loaded capsule 84 may then be stored in a suitable rack or similar device so that when it is desired to utilize the cards 16 at some future time, the operator may manually select the appropriate capsule by reading the various labels on the flanges on 148.

It will thus be seen that simple and inexpensive means have been provided for automatically loading stacks of data processing film cards into the various capsules in a group of similar capsules. These means are particularly adapted to being easily stored and/or readily handled with a minimum amount of equipment and/or expensive

tabs. While only a single embodiment of the present invention is disclosed and described herein, it will be readily apparent to persons skilled in the art that numerous changes and modifications may be made thereto without departing from the spirit of the invention. Accordingly the foregoing disclosure and description thereof are for illustrative purposes only and do not in any way limit the invention, which is defined only by claims which follow.

What is claimed is:

1. A device of the class described for use on a machine having a cutter for cutting a continuous strip of film into a plurality of cards and for stacking the cards in a stacked relationship, said device including:
- a capsule having a plurality of walls arranged to define a compartment for receiving a stack of said cards, the ends of at least a portion of said walls being positioned to form an opening substantially the same size as said cards, 15
- retaining means on at least one of said walls disposed adjacent the opening for engaging the end of said stack to prevent the cards therein from passing through said opening, 20
- resilient means effective to bias said stack axially of said compartment and against said retaining means, 25
- a magazine for being releasably secured in position on said machine adjacent said cutter, 30
- means on said magazine for receiving said capsule and positioning said opening adjacent said cutter in substantially alignment with the cards being cut by said cutter,
- means on said magazine movable between a first position to permit said capsule to move into and out of said receiving means and a second position effective to secure said capsule in said receiving means 35
- on said magazine, said last means when in said second position being effective to engage said retaining means and at least partially release the cards in said stack, and 40
- means on said magazine for preventing said resilient means from biasing said cards through said opening.
2. A device of the class described for use on a machine having a cutter for cutting a continuous strip of film into a plurality of cards and for stacking the cards in a stacked relationship, said device including:
- a capsule having a plurality of walls arranged to define a compartment for receiving a stack of said cards, the ends of at least a portion of said walls being positioned to form an opening substantially the same size as said cards, 50
- retaining means on at least one of said walls disposed adjacent the opening for engaging the end of said stack to prevent the cards therein from passing through said opening, 55
- a magazine for being releasably secured in position on said machine adjacent said cutter, 60
- means on said magazine for receiving said capsule and positioning said opening adjacent said cutter in substantial alignment with the cards being cut by said cutter,
- means on said magazine movable between a first position to permit said capsule to move into and out of said receiving means and a second position effective to secure said capsule in said receiving means 65
- on said magazine, said last means when in said second position being effective to engage said retaining means and at least partially release the cards in said stack,
- resilient means on said magazine for acting against said stack to bias said stack toward said opening and to retain said capsule against said last means, and 70
- means on said magazine for preventing said resilient means from biasing said cards through said opening. 75

3. In combination for use on a machine for cutting a continuous strip of film into a plurality of cards and for stacking the cards in a stacked relationship,

- means for cutting the film strip into cards, 5
- a capsule having at least a pair of walls arranged to define the opposite sides of a compartment for receiving a stack of said cards, said pair of walls being resiliently deflectable toward and away from each other, said walls having ends normally positioned to form the opposite sides of an opening substantially the same size as said cards,
- at least one lip on at least one of said walls disposed adjacent said opening and projecting inwardly toward the opposite wall for engaging the card on the end of said stack to retain said stack within said compartment,
- a magazine releasably secured in position on said machine adjacent said cutting means,
- first means on said magazine for receiving said capsule and positioning said opening adjacent said cutting means in substantial alignment with the cards being cut from said film by said cutting means,
- second means on said magazine and movable between a first position to permit said capsule to move into and out of said receiving means and a second position effective to secure said capsule in said receiving means on said magazine,
- third means on said last means for engaging said walls when said last means are in said second position to separate said lips by a distance greater than the width of said cards to provide for a passage of cards into the magazine, and
- means on said magazine for releasably retaining the second means in the second position.
4. In combination for use on a machine having a cutter for cutting a continuous strip of film into a plurality of cards and for stacking the cards in a stacked relationship,
- a capsule having at least a pair of walls arranged to define the opposite sides of a compartment for receiving a stack of said cards, said pair of walls being resiliently deflectable toward and away from each other, said walls having ends normally positioned to define the opposite sides of an opening substantially the same size as said cards,
- at least one lip on at least one of said walls disposed adjacent said opening and projecting inwardly toward the opposite wall for engaging the card on the end of said stack to retain said stack within said compartment,
- first means to resiliently bias said stack axially of said compartment and against said lips,
- a magazine releasably secured in position on said machine adjacent said cutter,
- second means on said magazine for receiving said capsule and positioning said opening adjacent said cutter in substantial alignment with the cards being cut from said film by said cutter,
- retaining means on said magazine movable between a first position to permit said capsule to move into and out of said receiving means and a second position effective to secure said capsule in said receiving means on said magazine,
- third means on said retaining means for engaging said walls when said last means are in said second position to separate said lips by a distance at least corresponding to the width of said cards,
- second resilient means on said magazine to co-act with said first resilient means to bias said stack and said capsule toward said retaining means, and
- means on said magazine for engaging the capsule to prevent said resilient means from biasing said cards through said opening but to permit said cutter to force said cards through said opening and onto said stack.
5. The combination set forth in claim 4, including, means on the magazine and on the retaining means

for providing a cooperative relationship to retain the retaining means in the second position, and means operative upon the last mentioned means to provide a release of the last mentioned means from the cooperative relationship for a change in the retaining means from the second position to the first position.

6. A device of the class described for use on a machine having a cutter for cutting a continuous strip of film into a plurality of cards and for retaining the cards in a stacked relationship, said device including:

a capsule having at least a pair of walls arranged to define the opposite sides of a compartment for receiving a stack of said cards, said pair of walls being resiliently deflectable toward and away from each other and having their ends positioned to form the opposite sides of an opening substantially the same size as said cards,

at least one lip on each of the walls in said pair disposed adjacent said opening and projecting inwardly for engaging the card on the end of said stack to retain said stack within said compartment,

means to resiliently bias said stack axially of said compartment and against said lips, a magazine for being releasably secured in position on said machine adjacent said cutter,

means on said magazine for receiving said capsule and positioning said opening adjacent said cutter in substantial alignment with the cards being cut from said film by said cutter,

a lever pivotably mounted on said magazine for movement between a first position and a second position, said lever when in said first position being effective to permit said capsule to be removed from said receiving means on said magazine, said lever when in the second position extending across said end of said capsule to secure said capsule in position on said magazine,

means on said lever positioned to engage said walls to move them outwardly and separate said lips by a distance greater than the width of said cards, and second retaining means on said lever for preventing said resilient means from biasing said cards through said opening but permitting said cutter to force said cards through said opening and into said compartment.

7. In a device of the class described for use with a machine for producing a series of film cards, means for accumulating said film cards as they are produced and storing the cards in a stacked relationship suitable for future use, the combination of:

a group of substantially identical capsules, each of the capsules in said group having at least a pair of walls arranged to define the opposite sides of a compartment for receiving and storing a stack of said cards, said pair of walls being resiliently deflectable toward and away from each other and having their ends positioned to form the opposite sides of an opening substantially the same size as said cards,

means on each of the walls in said pair disposed adjacent said openings and projecting inwardly for engaging the card on the end of said stack to retain said stack within said compartment,

means to resiliently bias said stack axially of said compartment and against said lips,

a magazine having a capsule receiving portion for receiving one of the capsules in said group,

means on said magazine for releasably securing a capsule in said receiving portion,

means on said magazine for releasably mounting said magazine on said machine and positioning said opening of the received capsule to receive the cards as they are produced by said machine.

8. Apparatus for cutting a continuous strip of film having a series of frames into a plurality of film cards with each card containing a frame and for stacking said cards, said apparatus including:

a film guide for receiving said strip of film and allowing said strip to travel therethrough and emerge from one end of said guide,

feed means for intermittently advancing the strip of film through said film guide in lengths substantially equal to the length of a frame to thereby momentarily position the terminal frame on said strip adjacent said end of said guide,

a cutting head disposed adjacent the end of said guide, a cutting edge on said head for engaging said film along the edge of the terminal frame for cutting a film card from said strip containing said frame, a cutting head drive operatively coupled to said cutting head and to stop means and effective when the film strip stops to actuate said cutting head for cutting said card from the film strip,

a capsule including an opening in one end for receiving said cards and accumulating a stack, fastening means for securing said capsule in position adjacent said cutting means,

retaining means on said capsule adjacent said opening positioned to retain a stack of cards in said capsule, said fastening means including means to at least partially disable said retaining means to permit cards to pass therethrough,

second retaining means on said fastening means for retaining said cards in said capsule but permitting the said cards to pass therethrough, and

means on said head for engaging said card as it is cut from said strip to simultaneously force said card through said opening and into said capsule.

9. Means for cutting a strip of film having a series of frames into a plurality of film cards with each card containing a frame and for stacking said cards, said means including:

a film guide having a passage for receiving said strip of film and allowing said strip to travel therethrough and emerge from one end of said guide,

a magazine for being releasably secured adjacent said guide means,

a capsule mounted on said magazine and including an opening for receiving said cards and accumulating a stack of cards, said magazine being effective to position said opening in substantial alignment with the frames emerging from said guide,

retaining means on said capsule adjacent said opening positioned to retain a stack of cards in said capsule, means on said magazine for securing said capsule in position on said magazine,

means for at least partially disabling said first retaining means and being effective to retain said stack in said capsule,

feed means for intermittently advancing the strip of film through said film guide and beyond said end in increments substantially equal to the length of a frame to thereby momentarily position the terminal frame on said film strip adjacent said end of said guide,

a cutting head disposed adjacent said end of said guide and in substantial alignment with said opening for moving between an extended position adjacent said opening and a retracted position away from said opening,

a cutting edge on said head positioned to engage said film strip along the edge of said terminal frame for cutting a film card from said strip when said cutting head moves into said extended position, and

means on said head for engaging said card as it is cut from said strip to simultaneously force said card through said opening and into said capsule.

10. In combination for cutting a strip of film into a plurality of film cards and for stacking the cards in a stacked relationship,

means for intermittently advancing the film strip, means operatively coupled to the advancing means for

obtaining an interruption in the advance of the film strip after the film strip has been advanced through each successive increment,
 cutting means operatively coupled to the film strip and responsive to each interruption in the advance 5 of the film for engaging and cutting the film into film cards,
 a capsule including an opening in one end for receiving said cards as they are cut from said film,
 first retaining means on said capsule adjacent said opening, the retaining means being positioned to retain the cards in the stacked relationship in said capsule, the first retaining means being movable between first and second positions and being operative 10 in the first position to retain the cards within the capsule and prevent the passage of cards into the capsule and being operative in the second position to provide for a passage of cards into the capsule, a magazine having a portion for receiving said capsule, means on said magazine for securing said capsule in 15 position on said magazine and positioning said opening adjacent said cutting means for receiving said cards as they are being cut,
 second retaining means on said securing means for retaining said cards in said capsule but permitting said cards to pass therethrough, the second retaining means being movable between first and second positions and being operative in the first position to provide for a removal of the capsule from the magazine 20 and being operative in the second position to retain the capsule in fixed position on the magazine and to move the first retaining means to the second position, and
 means on said cutting means for inserting the resultant cards through said second retaining means 25 and into the capsule simultaneously with the engagement of the film by the cutting means for the purpose of performing the cutting operation.
 11. The combination set forth in claim 10, including, means on the magazine and operatively coupled to the last mentioned means for releasably retaining the last mentioned means in the second position. 40
 12. The combination set forth in claim 11, including, means for moving a film strip past the opening in the capsule, and 45 means for cutting the film strip into cards and for storing the cards in the capsule in the second position of the retaining means.
 13. The combination set forth in claim 12 wherein the combination is used for cutting a film into the plurality 50 of cards and for stacking the cards, including, means on the magazine and on the last mentioned means for releasably retaining the last mentioned means in the second position, means for advancing the film past the opening in the 55 capsule, and means for cutting the film into the cards and passing the cards through the opening in the capsule in the second position of the retaining means.
 14. In combination for receiving and stacking a plurality 60 of cards, a magazine having a capsule receiving portion, a capsule releasably mounted on said capsule receiving portion of said magazine for being releasably retained thereon, said capsule including an opening 65 in one end for receiving cards, retaining means on said capsule adjacent said opening, said retaining means normally being disposed in a first position to retain a stack of cards within said capsule to prevent said cards passing through said opening and being movable to a second position to provide for a transfer of cards into the capsule through the opening in the capsule, 70 means for resiliently biasing said stack against said retaining means, and

means on said magazine and having first and second positions and disposed in the first position to provide for a removal of the capsule from the magazine and disposed in the second position to engage the retaining means on the magazine for moving the retaining means from the first position to the second position.
 15. In combination in a machine for stacking a plurality of substantially identical cards, support means, a magazine releasably secured in position on said support means, a capsule receiving portion on said magazine, a capsule releasably mounted on said portion and including an opening in one end, retaining means on said capsule positioned adjacent said opening and movable between first and second positions, said retaining means normally being disposed in the first position to retain the stack of cards disposed inside of said capsule and to prevent said cards from passing through said opening and being movable to a second position to provide for a passage of cards through said opening, means for resiliently biasing said stack against said retaining means, and means on said magazine and having first and second positions and disposed in the first position to provide for a removal of the capsule from the magazine and disposed in the second position to prevent the removal of the capsule from the capsule-receiving portion of the magazine and to obtain the movement of the retaining means to the second position.
 16. In combination for use in a machine for stacking a plurality of substantially identical cards, said device including, support means, a magazine releasably secured in position on said support means, a capsule receiving portion on said magazine, a capsule releasably mounted on said capsule-receiving portion and including an opening in one end, first retaining means resiliently disposed on said capsule adjacent said opening and having first and second positions, said retaining means normally being disposed in the first position to retain the cards within said capsule and to prevent said cards from passing through said opening and movable to the second position to provide for a passage of the cards into the capsule through the opening in the capsule, first resilient means disposed inside of said capsule for biasing said cards within the capsule against said retaining means, second retaining means on said magazine and having first and second positions and extending across said end of said capsule in the first position to retain said capsule positioned in said capsule-receiving portion and to move the retaining means to the second position and movable to the second position to provide for a removal of the capsule from the magazine, and second resilient means on said magazine for biasing said capsule against said last means to retain said capsule in position on said magazine, said second resilient means being effective to co-act with said first resilient means to further bias the cards in the capsule toward the opening.
 17. The combination set forth in claim 16, including, means on the magazine and on the second retaining means for releasably retaining the second retaining means in the first position, and means operatively coupled to the last mentioned means for operating on the last mentioned means to provide for a movement of the second retaining means from the first position to the second position.
 18. In combination for storing cards in a stacked relationship,

a capsule having a plurality of wall members resiliently arranged to define a compartment for receiving a stack of said cards, at least a pair of said wall members having their ends spaced to form an opening in one end of said capsule to permit cards to pass therethrough into and out of said compartment and being resiliently movable toward and away from each other, at least one lip on at least one of the walls in said pair, the lip being disposed adjacent said opening and extending inwardly toward the opposite wall to engage the end of said stack and retain the cards therein within said compartment, 5
 resilient means on said capsule, the resilient means being disposed to bias said stack toward said opening and against said lip, 10
 support means, a magazine releasably secured to said support means, a capsule-receiving portion on said magazine for receiving said capsule, 15
 a lever having a pair of arms spaced from each other to define an opening and pivotably mounted on said magazine and movable between a first position and a second position, said lever when in said first position disposed to permit said capsule to be inserted into and removed from said portion, 20
 said lever when in said second position having its arms disposed over said capsule to retain said capsule on said magazine and provide the opening between the arms in substantial alignment with said opening in said capsule for a passage of the cards through the opening, and 25
 means on each of said arms for engaging the walls in said pair in the second position of the lever to separate said lip and the opposite wall by a distance at least corresponding to the width of said cards. 30
 19. The combination set forth in claim 18, including, a lip on at least one of said arms and extending into said opening between the arms, said lip on the arm being constructed and disposed to retain said cards in said capsule and to permit said cards to pass through said opening and into said capsule. 35
 20. In combination for storing cards in a stacked relationship, a capsule having a plurality of wall members arranged to define a compartment for receiving a stack of said cards, at least a pair of said wall members having ends spaced to form an opening in one end of said capsule to permit cards to pass therethrough into and out of said compartment, the wall members in said pair being resiliently deflectable toward and away from each other, 40
 at least one lip on at least one of the walls in said pair, said lip being disposed adjacent said opening and extending inwardly toward the opposite wall to retain the cards within said compartment, 45
 resilient means in said capsule, the resilient means being disposed to bias said cards toward said opening and against said lip, 50
 support means, a magazine releasably secured to said support means, a capsule-receiving portion on said magazine for receiving said capsule, 55
 a lever having a pair of arms pivotably mounted on said magazine and movable between a first position and a second position and spaced from each other to define an opening, said lever when in said first position being disposed to permit said capsule to be inserted into and removed from said portion, 60
 said lever when in said second position having its arms disposed over said capsule to retain said capsule positioned on said magazine and provide the opening between the arms in substantial alignment with said opening in said capsule, 65
 70
 75

detent means on said magazine for retaining said lever releasably locked in said second position, and wedge means on each of said arms for engaging a wall in said pair on said capsule to thereby move said walls apart and separate said lip from the opposite wall by a distance at least corresponding to the width of said cards. 5
 21. The combination set forth in claim 20, including, a lip on at least one of said arms extending into said opening between the arms, said lip on said arm being constructed and disposed to retain said cards in said capsule but to permit said cards to pass through said opening between the arms and into the capsule. 10
 22. In combination for storing cards in a stacked relationship suitable for future use, a group of substantially identical capsules, each of said capsules having a compartment therein for receiving said film cards and an opening in one end for said cards to pass into and out of said compartment, 15
 retaining means resiliently disposed on each of said capsules adjacent said opening, said retaining means normally being disposed in a first position to retain the cards within the capsule to prevent said cards passing through said opening and being resiliently movable to a second position to provide for a passage of cards into the capsule, 20
 a magazine having a capsule receiving portion for receiving one of the capsules in said group, and means on said magazine and movable between first and second positions and disposed in the first position for releasably securing one of said capsules in said magazine and moving said retaining means from the first position to the second position to permit said cards to pass through said opening and movable to a second position to provide for a removal of the capsule from the magazine. 25
 23. The combination set forth in claim 22, including, means on said magazine and operatively coupled to the last mentioned means for releasably retaining the last mentioned means in the first position. 30
 24. In combination for cutting a strip of film into a plurality of film cards and for stacking the cards in a stacked relationship, means for intermittently advancing the film strip, means operatively coupled to the advancing means for obtaining an interruption in the advance of the film strip after the film strip has been advanced through each successive increment, 35
 cutting means operatively coupled to the film strip and responsive to each interruption in the advance of the film strip for engaging and cutting the film into film cards, 40
 a capsule including an opening in one end for receiving said cards, 45
 retaining means on the capsule adjacent said opening, the retaining means being constructed and positioned to retain a stack of cards in said capsule, the retaining means being normally disposed in a first position to retain the cards in the capsule and being movable to a second position to provide for a passage of cards into and out of the capsule, 50
 means for securing said capsule adjacent said cutting means, said securing means including means movable between first and second positions and operative in the first position to move said retaining means to the second position to permit cards to pass through the opening in the capsule and being movable to the second position to provide for a removal of the capsule from the securing means, and means on said cutting means for inserting the resultant cards through the opening in said retaining means 55
